UNITED STATES PATENT OFFICE

AARON E. JENNINGS, OF CENTRAL CITY, KENTUCKY

DESIGN FOR AN AUTOMOBILE TIRE

Application filed April 15, 1929. Serial No. 30,912. Term of patent 7 years.

To all whom it may concern:

Be it known that I, AARON E. JENNINGS, a citizen of the United States, residing at Central City, in the county of Muhlenberg and State of Kentucky, have invented a new, original, and ornamental Design for an Automobile Tire, of which the following is a specification, reference being had to the accompanying drawings, which form a part thereof, and in which—

Figure 1 is a side elevation of a portion

of an automobile tire, showing my new design; and Figure 2 is a top view of the same when viewed from a level plane, and not circumferentially disposed.

I claim:

The ornamental design for an automobile tire as shown and described.

In testimony whereof I hereunto affix my signature.

AARON E. JENNINGS.
